His Attorney.

UNITED STATES PATENT OFFICE

PAUL N. BOSSART, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed July 9, 1929. Serial No. 377,040.

My invention relates to railway traffic controlling apparatus, and particularly to apparatus of the type wherein periodically interrupted currents are supplied to the track rails for the control of trains.

I will describe one form of apparatus embodying my invention, and will then point out the novel features thereof in claims.

The accompanying drawing is a diagrammatic view illustrating one form of apparatus embodying my invention.

Referring to the drawing, the reference characters 41 and 41^a designate the track rails of a stretch of railway track over which traffic normally moves in the direction indicated by the arrow, and which rails are divided into sections by means of insulated joints 42. For purposes of illustration I have shown my invention as applied to the exit end of only one track section, but it will be readily understood that in actual practice similar apparatus may be applied to each track section over an extended stretch of track.

The track rails 41 and 41^a are supplied with current from a track transformer T, the secondary 30 of which is constantly connected with the rails through a reactance X adjacent the exit end of the section. The primary 29 of transformer T is at times supplied with alternating current from the secondary 32 of a transformer L, the primary 33 of which is constantly connected with an alternator G.

The supply of current to the primary 29 of transformer T is controlled by a relay E which, in turn, is controlled by traffic conditions in a manner not shown. The supply of current to the primary 29 of transformer T is also controlled by coding apparatus embodying my invention, which is designated, in general, by the reference character D, and which I will now describe.

The coding apparatus D comprises a contact mechanism which is periodically operated at a constant frequency, and two neutral relays A and B of any suitable type. As here shown, the contact mechanism is a flasher relay C comprising a winding 38 and three contacts 37, 1 and 35, but this type of contact mechanism is not essential to my invention. Relay A is provided with a main winding 2

having a relatively large number of turns, an auxiliary winding 3 having a relatively small number of turns, and two contacts 4 and 5. Relay B is provided with a winding 7 and a contact 8.

The winding 38 of relay C is supplied with current over its one back contact 37 from a battery R, and it will be apparent, therefore, that relay C will become energized and de-energized alternately, so that its contacts are periodically opened and closed. The parts of relay C are so proportioned that this alternate energization and de-energization will take place at a constant predetermined frequency. The relays A and B are controlled by contact 1 of relay C. As shown in the drawing, relays A and B are both de-energized and contact 1 is open. Under these conditions, when contact 1 closes current flows from a suitable source of electromotive force, here shown as a battery 9, through wire 10, a fuse 11, wire 12, winding 3 of relay A, wires 13 and 14, winding 7 of relay B, wires 15 and 16, back point of contact 4 of relay A, wire 17, front contact 1 of relay C, and wires 19 and 20 back to battery 9. The parts are so proportioned that this current flowing in winding 3 of relay A does not energize relay A, but this current flowing in winding 7 of relay B is sufficiently large to energize relay B. When relay B becomes energized it closes its front contact 8, and as long as contact 1 remains closed, winding 2 of relay A is then short-circuited over a circuit which passes from winding 2 through wire 22, front contact 8 of relay B, wires 23 and 19, front contact 1 of relay C, wire 17, back point of contact 4 of relay A, and wires 16 and 21 back to winding 2 of relay A. When contact 1 opens, however, this short circuit is opened and winding 2 is then included in a circuit which passes from battery 9 through wire 10, fuse 11, wire 12, winding 3 of relay A, wires 13 and 14, winding 7 of relay B, wires 15 and 21, winding 2 of relay A, wire 22, front contact 8 of relay B, and wires 23 and 20 back to battery 9.

Windings 2 and 3 of relay A are connected in this latter circuit in such manner that the fluxes produced in core 6 of relay A by the current flowing in these windings are addi-

tive and relay A therefore becomes energized. When relay A becomes energized, contact 4 opens its back point and closes its front point, and contact 5 becomes closed. It will be noted that winding 7 of relay B is also included in the circuit last traced so that as long as this circuit is closed, relay B remains energized and holds its contact 8 closed. As a result, when contact 1 next closes, winding 10 2 of relay A and winding 7 of relay B are short-circuited over a circuit which passes from winding 2 of relay A through wires 21 and 15, winding 7 of relay B, wires 14 and 24, front point of contact 4 of relay A, wire 15 17, front contact 1 of relay C, wires 19 and 23, front contact 8 of relay B, and wire 22 back to winding 2. This short circuit causes relay B to become de-energized, but relay A remains energized because, under these conditions, a 20 large current is supplied to winding 3 of relay A over a circuit which passes from battery 9 through wire 10, fuse 11, wire 12, winding 3 of relay A, wires 13 and 24, front point of contact 4 of relay A, wire 17, front 25 contact 1 of relay C, and wires 19 and 20 back to battery 9. When contact 1 next opens, however, the circuit just traced is interrupted and relay A then becomes de-energized so that contact 4 opens its front point and closes its 30 back point, and contact 5 opens. The parts of the coding apparatus D are then restored to the positions in which they are illustrated in the drawing, and when contact 1 next closes, the cycle of events just described starts 35 to repeat itself.

It should be pointed out that, in actual practice, the resistance of the circuit which is completed when contact 1 of relay C and front point of contact 4 of relay A are both closed 40 is practically all due to the resistance of winding 3 of relay A. As a result, if some of the turns of winding 3 become short-circuited for any reason, the current flowing in the turns of winding 3 which are not short-circuited 45 will increase by an amount which is proportional to the decrease in resistance of this circuit due to the short-circuited turns, and the ampere turns acting on core 6 of relay A would therefore remain substantially constant, so that the coding apparatus would 50 continue to function in the manner described. Furthermore, if the connections to winding 3 are made in such manner that the external circuit makes at least a portion of a turn 55 around core 6 of relay A, then, in the event of a total short circuit on winding 3, the ampere turns acting on core 6 of relay A would still remain constant for the reasons pointed out above, and the apparatus would function as 60 described. It will be noted, however, that a fuse 11 is included in the circuit for winding 3, and this fuse is so proportioned that, in case the winding 3 is completely short-circuited, the fuse will blow out, thereby pro-

tecting battery 9. This fuse, however, is not essential to my invention.

From the foregoing it will be apparent that relay A becomes energized one time each two times contact 1 is opened and closed, and it follows, therefore, that relay A is energized one time each two times relay C is operated. Contact 5 of relay A is closed each time relay A is energized. It follows, therefore, that contact 5 is periodically opened and closed at half the frequency at which relay C is operated. It should be noticed, also, that contact 5 is opened and closed equal intervals of time.

When relay E is energized, primary 29 of transformer T is supplied with current over a circuit which is periodically interrupted by contact 35 of relay C and which passes from secondary 32 of transformer L through wire 31, primary 29 of transformer T, wire 28, front point of contact 27 of relay E, wire 36, front contact 35 of relay C, and wires 34 and 25 back to secondary 32. It will be apparent, therefore, that under these conditions the train controlling current supplied to the track rails 41 and 41^a from secondary 30 of transformer T is periodically interrupted at the frequency of operation of relay C. When relay E is de-energized, however, primary 29 of transformer T is then supplied with current over a circuit which is periodically interrupted by front contact 5 of relay A and which passes from secondary 32 of transformer L through wire 31, primary 29 of transformer T, wire 28, back point of contact 27 of relay E, wire 26, front contact 5 of relay A, and wire 25 back to secondary 32 of transformer L. Under these latter conditions, the track rails 41 and 41^a are supplied with train controlling current from the secondary 30 of transformer T which is periodically interrupted at the frequency of operation of relay A. Since relay A operates at half the frequency of relay C, it will be apparent that the current supplied to the track rails is periodically interrupted at one frequency when relay E is energized, and at half this frequency when relay E is de-energized.

The apparatus shown herein is suitable for cooperation with train carried mechanism receiving energy from the track rails and selectively responsive to the frequency at which the train controlling current in the rails is interrupted.

While I have illustrated coding apparatus embodying my invention as applied to the control of trackway currents in a train control system, it should be particularly pointed out that my invention is not limited to this use but is applicable wherever it is desired to operate one contact at half the frequency at which another contact is periodically operated.

Although I have herein shown and described only one form of apparatus embody-

ing my invention, it is understood that various changes and modifications may be made therein within the scope of the appended claims without departing from the spirit and scope of my invention.

Having thus described my invention, what I claim is:

1. In combination, a stretch of railway track, a contact mechanism which is periodically operated, two relays, means controlled by said contact mechanism and by both said relays for energizing one of said relays one time each two times said contact mechanism is operated, a source of train controlling current, and means for supplying current from said source to the rails of said stretch under the control of said contact mechanism or said one relay in accordance with traffic conditions.
2. In combination, a stretch of railway track, a contact mechanism which is periodically operated, two relays, means controlled by said contact mechanism and by both said relays for energizing said relays one time each two times said contact mechanism is operated, means controlled by said contact mechanism for at times supplying train controlling current to the rails of said stretch, and means controlled by one of said relays for at other times supplying train controlling current to the rails of said stretch.
3. In combination, a stretch of railway track, a contact mechanism which is periodically operated, two relays, means controlled by said contact mechanism and by both said relays for alternately energizing said relays one time each two times said contact mechanism is operated, means controlled by said contact mechanism for at times supplying train controlling current to the rails of said stretch, and means controlled by one of said relays for at other times supplying train controlling current to the rails of said stretch.
4. In combination, a stretch of railway track, a first relay which is energized and de-energized alternately, a second and a third relay, means for at times energizing said second relay when said first relay becomes energized, means for energizing said third relay when said first relay subsequently becomes de-energized, means for de-energizing said second relay when said first relay next becomes energized, means for de-energizing said third relay when said first relay again becomes de-energized, a source of train controlling current, and means responsive to traffic conditions for at times connecting said source with the rails of said stretch over a contact of said third relay.
5. In combination, a stretch of railway track, a contact mechanism comprising a contact which is periodically opened and closed, a first and a second relay, means for energizing the first relay when said contact becomes closed, means for energizing the second relay when said first relay is energized and said contact is subsequently opened, means for de-energizing said first relay when said second relay is energized and said contact next becomes closed, means for de-energizing said second relay when said contact is again opened, a source of train controlling current, and means for supplying current from said source to the rails of said stretch under the control of said contact mechanism or said second relay in accordance with traffic conditions.
6. In combination, a stretch of railway track, a first relay which is energized and de-energized alternately, a second and a third relay, means including a back contact of said second relay for at times energizing said third relay when said first relay becomes energized, means including a front contact of said third relay for energizing said second relay when said first relay is subsequently de-energized, means including a front contact of said second relay for de-energizing said third relay when said first relay next becomes energized, means for maintaining said second relay in its energized condition after said third relay becomes de-energized until said first relay again becomes de-energized, a source of train controlling current, and means for supplying current from said source to the rails of said stretch under the control of said first relay or said second relay in accordance with traffic conditions.
7. In combination, a stretch of railway track, a contact mechanism comprising a first contact which is periodically opened and closed, a first and a second relay, means including a back contact of said first relay for at times energizing said second relay when said first contact becomes closed, means including a front contact of said second relay for energizing said first relay when said first contact is subsequently opened, means including a front contact of said first relay for de-energizing said second relay when said first contact next becomes closed, means including a front contact of said first relay for maintaining said first relay in its energized condition after said second relay becomes de-energized until said first contact is again opened, a source of train controlling current, and means for supplying current from said source to the rails of said stretch under the control of said contact mechanism or said first relay in accordance with traffic conditions.
8. In combination, a stretch of railway track, a contact mechanism comprising a first contact which is periodically opened and closed, a first relay having a first and a second winding, a second relay having a third winding, a first circuit including said second closed, a first and a second relay, means for winding, said third winding, a back contact

of said first relay, and said first contact; a second circuit including said second winding, said third winding, said first winding, and a front contact of said second relay; a third circuit including said second winding, a front contact of said first relay, and said first contact; a source of train controlling current, and means for supplying current from said source to the rails of said stretch under the control of said contact mechanism or said first relay in accordance with traffic conditions.

9. In combination, a stretch of railway track, a first relay which is periodically energized and de-energized, a second relay having a first and a second winding made up of a relatively large and a relatively small number of turns, respectively, a third relay having a third winding, a source of current; a first circuit including said source, said second winding, said third winding, a back contact of said second relay, and a front contact of said first relay; a second circuit including said source, said second winding, said third winding, said first winding, and a front contact of said third relay, said first and second windings being connected in said second circuit in such manner that the fluxes produced in the core of said second relay by current from said source in said windings are additive; a third circuit including said source, said second winding, a front contact of said second relay, and said front contact of said first relay; a source of train controlling current, and means for supplying current from said source to the rails of said stretch under the control of said first relay or said second relay in accordance with traffic conditions.

10. In combination, a stretch of railway track, a first relay which is periodically energized and de-energized, a second and a third relay, means for at times energizing said second relay when said first relay becomes energized, means for energizing said third relay when said second relay is energized and said first relay is subsequently de-energized, means for de-energizing said second relay when said third relay is energized and said first relay next becomes energized, means for maintaining said third relay in its energized condition after said second relay becomes de-energized until said first relay again becomes de-energized, a source of train controlling current, and means for supplying current from said source to the rails of said stretch under the control of said first relay or said third relay in accordance with traffic conditions.

11. In combination, a stretch of railway track, a contact mechanism comprising a first contact which is periodically opened and closed, two relays, means controlled by said first contact and by both said relays for energizing one of said relays each alternate time said first contact is opened and closed, a sec-

ond contact which is closed each time said one relay is energized, a source of train controlling current, and means for supplying current from said source to the rails of said stretch under the control of said contact mechanism or said second contact in accordance with traffic conditions.

12. In combination, a stretch of railway track, a contact mechanism comprising a contact which is periodically opened and closed, a first and a second relay, means for at times energizing said first relay when said contact becomes closed, means for energizing said second relay when said first relay is energized and said contact is subsequently opened, means for de-energizing said first relay when said second relay is energized and said contact next becomes closed, means for de-energizing said second relay when said contact is again opened, a source of train controlling current, and means for supplying current from said source to the rails of said stretch under the control of said contact mechanism or said first relay in accordance with traffic conditions.

13. In combination, a stretch of railway track, a contact mechanism which is periodically operated, a first and a second relay, means controlled by said contact mechanism and by said first and second relays for energizing said first relay one time each two times said contact mechanism is operated, a source of train controlling current, and means for supplying current from said source to the rails of said stretch under the control of said contact mechanism or said first relay in accordance with traffic conditions.

14. In combination, a stretch of railway track, a contact mechanism which is periodically operated, a first and a second relay, means controlled by said contact mechanism and by said first and second relays for energizing said first relay one time each two times said contact mechanism is operated, a third relay controlled by traffic conditions in said stretch, means including a front contact of said third relay and a contact of said contact mechanism for at times supplying the rails of said stretch with current, and means including a back contact of said third relay and a contact of said first relay for at other times supplying the rails of said stretch with current.

In testimony whereof I affix my signature.
